GAS BURNER ARRANGEMENT

Rudolf Schork, Wernau, Kreis Esslingen (Neckar), and Josef Schmid, Ludwigsburg, Germany, assignors to Firma Junkers & Co. G. m. b. H., Kreis Esslingen, Germany

Application July 14, 1954, Serial No. 443,322

Claims priority, application Germany July 23, 1953

3 Claims. (Cl. 158—140)

The present invention relates to gas burning installations.

In some gas burner installations there is a place adjacent the controls where the gas is always escaping to the atmosphere. This escaping gas, which is combustible, is extremely undesirable because there is always the danger of ignition of this gas. Such ignition will result, for example, in burning of the air to be sucked into the gas burner so that the combustion of the latter is very poor, and moreover the parts of the apparatus become heated to an undesirable extent producing unnecessarily high friction between moving parts.

One of the objects of the present invention is to improve an installation of the above type by preventing gas from leaking to the atmosphere.

Another object of the present invention is to utilize gas which would otherwise leak to the atmosphere.

A further object of the present invention is to arrange the apparatus in such a way that foreign matter cannot fall into the same to disturb the operation thereof.

With the above objects in view the present invention mainly consists of a gas burner arrangement which includes a conduit means for conveying a combustible gas. A valve means is located in the conduit means for controlling the flow of gas from a part of the conduit means downstream of the valve means to a part of the conduit means upstream of the valve means. An elongated valve operating member engages the valve means for operating the same, and a guide through which the operating member extends with clearance communicates with the interior of the conduit means so that the gas in the latter leaks through the guide. A gas burner means communicates with the conduit means at the part thereof downstream of the valve means, this burner means including a mixing tube in which the gases to be burned are mixed, and a duct communicates on the one hand with the guide to receive gases located therein and also communicates on the other hand with the mixing tube whereby gas leaking from the conduit means through the guide is delivered by the duct to the interior of the mixing tube of the gas burner means.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a fragmentary, partly sectional, elevational view of one possible apparatus for carrying out the present invention;

Fig. 2 illustrates a different embodiment of the apparatus of Fig. 1; and

Fig. 3 is a sectional elevational view of a third embodiment of an apparatus constructed in accordance with the present invention.

Referring now to the drawings, the embodiment of

2

Fig. 1 includes a gas valve housing 1 part of which is formed by a conduit 2 connected to a source of combustible gas by the dotted line conduit shown in the lower portion of Fig. 1. The conduit 3 conveys combustible gas to burners not shown in the drawings, the valve member 4 controlling the flow of gas from the conduit means located downstream of valve 4 to the conduit 3 located upstream of valve 4. This valve 4 is urged to its closed position by the spring 5 and is engaged by an elongated valve moving member in the form of rod 6. This rod 6 extends upwardly from valve member 4 and in the embodiment of Fig. 1 carries at its top end a projection which is engaged by a bimetallic strip 7. As is shown in Fig. 1, a flame, indicated in dotted lines, heats a member which transfers its heat to the strip 7 to cause the upper movable arm thereof to move downwardly so as to move pin 6 down, as viewed in Fig. 1, to open valve 4 against the action of spring 5.

When the valve is open gas will flow into conduit 3 and from the latter along a bore 9 of a guide 10, the pin 6 extending with clearance through the bore 9. Above this bore 9 the guide 10 is formed with an enlarged continuation of bore 9 leading to the outer atmosphere so that the gas leaking through bore 9 would simply flow to the outer atmosphere were it not for the structure of the invention described below. The enlarged continuation of bore 9 is formed in a member 11 screwed into the outer sleeve of guide 10. The member 11 is formed with a cutout 12 which serves to provide a communication between bore 9 and the continuation thereof and a duct 13 connected at its left end, as viewed in Fig. 1, to the guide 10. The opposite end of duct 13 communicates with the primary air suction opening in the mixing tube of a gas burner 8.

The gas flowing to the outlet nozzle of burner 8 sucks not only the gas leaking through bore 9 but also sucks into the mixing tube of burner 8 primary air derived through the enlarged continuation of bore 9, as is evident from Fig. 1. The burner 8 communicates directly with the conduit shown in dotted lines in Fig. 1 so that the supply of gas to burner 8 is uninfluenced by valve 4. It will be noted that with this arrangement the duct 13 determines the position of burner 8 and controls its distance from bimetallic strip 7.

The embodiment illustrated in Fig. 2 differs from that of Fig. 1 only in that the top end of guide 10 is covered so that downwardly falling foreign matter, falling, for example, from a heat exchanger located over pin 6, cannot fall into the guide and create disturbances. Thus, instead of being open at the top, the embodiment of Fig. 2 is provided adjacent the closed top of guide 10 with lateral openings 14 communicating with the outer atmosphere.

According to the embodiment shown in Fig. 3, a unitary valve arrangement is provided. Thus, the valve housing 1' is formed with a passage constituting the conduits 2' and 3' respectively located downstream and upstream of the valve member 4' urged by spring 5' to its closed position. The valve operating pin 6' engages valve member 4' and extends to the exterior of housing 1' where the free end of pin 6' is located adjacent the bimetallic strip 7 to be operated thereby in the manner described above. The guide bore 9' which forms a guide for the pin 6' is of somewhat larger cross section than the latter so that gas escapes through bore 9' when valve 4' is open. The guide of Fig. 3 further includes the member 11' carried by housing 1' and formed with an axial bore through which pin 6' slidably extends. The burner 8' also is carried by housing 1' and communicates with the gas passage downstream of valve 4' through an inclined bore formed in the housing 1', as shown in Fig. 3. This burner 8' further communicates with one end of a bore

15 which in the embodiment of Fig. 3 constitutes the duct for the primary air sucked into the mixing tube of burner 8'. The bore 15 extends across bore 9' and has its lower end, as viewed in Fig. 3, in communication with the outer atmosphere. Thus, air sucked into burner 8' along bore 15 will also draw into burner 8' gas which leaks through the bore 9', so that the embodiment of Fig. 3 produces the same results as the embodiments of Figs. 1 and 2. Furthermore, when the embodiment of Fig. 3 is in its operating position shown in Fig. 3, the location of the inlet end of bore 15 beneath bore 9' and pin 6' prevents foreign matter from entering into the apparatus.

It will be seen that the structure of the invention prevents an uncontrolled escape of gas and in addition sucks this escaping gas with the gas mixing in the burner 8 or 8' so that even when rich gases such as propane or butane, which are heavier than air, are used, the leaking gas is efficiently delivered to the burner 8 or 8' and cannot cause any undesirable results.

It will be understood that each of the elements described above, or two or more together, may also find a useful application in other types of gas burners differing from the types described above.

While the invention has been illustrated and described as embodied in valve arrangement for gas burners, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitutes essential characteristics of the generic or specific aspects of this invention and, therefore, such adaptations should and are intended to be comprehended within the meaning and range of equivalence of the following claims.

What is claimed as new and desired to be secured by Letters Patent is:

1. In a gas burner arrangement, in combination, conduit means for guiding gas; valve means located in said conduit means for controlling the flow of gas therethrough; an elongated valve operating member engaging said valve means for operating the same; a guide through which said operating member extends with clearance, said guide being carried by said conduit means and communicating with the interior thereof so that gas in said conduit means may leak through said guide; gas burner means including a mixing tube carried by and communicating with said conduit means ahead of said valve means independently and separately of said guide so that the supply of gas to said burner means is uninfluenced by said valve means; and a duct communicating at one end with the atmosphere, at its other end with said mixing tube and at a point intermediate said end, with said guide, whereby gas leaking from said conduit means through said guide is sucked by fresh air passing through said duct to the interior of said mixing tube and therethrough to said burner means, thereby avoiding leakage of gas through said guide into the atmosphere.

2. In a gas burner arrangement, in combination, conduit means for conveying a combustible gas and including a housing; valve means located in said conduit means for controlling the flow of gas from a part of said con-

duit means upstream of said valve means to a part of said conduit means downstream of said valve means; an elongated valve operating member engaging said valve means for operating the same; a guide through which said operating member extends with clearance to be guided thereby, said guide communicating with the interior of said conduit means so that gas in the latter may leak through said guide; gas burner means carried by said housing independently of and spaced from said guide and communicating with said conduit means at said part thereof upstream of said valve means, said burner means including a mixing tube in which the gases to be burned are mixed; and a duct communicating with said guide to receive gases located therein and also communicating with said mixing tube whereby gas leaking from said conduit means through said guide is delivered by said duct to the interior of said mixing tube of said burner means, said conduit means being formed by a passage extending through said housing which carries said gas burner means, said housing being formed with a first bore forming said guide and with a second bore forming said duct, said second bore communicating at one end with the outer atmosphere, crossing over said first bore, and communicating at an opposite end with the interior of said mixing tube.

3. In a gas burner arrangement, in combination, conduit means for conveying a combustible gas and including a housing; valve means located in said conduit means for controlling the flow of gas from a part of said conduit means upstream of said valve means to a part of said conduit means downstream of said valve means; an elongated valve operating member engaging said valve means for operating the same; a guide through which said operating member extends with clearance to be guided thereby, said guide communicating with the interior of said conduit means so that gas in the latter may leak through said guide; gas burner means carried by said housing independently of and spaced from said guide and communicating with said conduit means at said part thereof upstream of said valve means, said burner means including a mixing tube in which the gases to be burned are mixed; and a duct communicating with said guide to receive gases located therein and also communicating with said mixing tube whereby gas leaking from said conduit means through said guide is delivered by said duct to the interior of said mixing tube of said burner means, said conduit means being formed by a passage extending through said housing which carries said gas burner means, said housing being formed with a first bore forming said guide and with a second bore forming said duct, said second bore communicating at one end with the outer atmosphere, crossing over said first bore, and communicating at an opposite end with the interior of said mixing tube, and said one end of said second bore being located, in the operating position of said housing, below said first bore and said valve operating member.
